WORK BENCH AND TABLE COMBINATION

Lowell R. Baumker, Toledo, Ohio, assignor to Baumker Manufacturing Company, Toledo, Ohio, a corporation of Ohio

Application January 24, 1955, Serial No. 34,166

Term of patent 14 years

(Cl. D33—14)

FIG. 1

I claim:

The ornamental design for a work bench and table combination, as shown.
